PASSENGER CAB FOR AMUSEMENT RIDE

Samuel P. Goforth and Joseph A. Goforth, Shelby, N.C.,
assignors to Goforth Brothers, Inc., Shelby, N.C., a cor-
poration of North Carolina

Filed July 25, 1967, Ser. No. 7,973

Term of patent 14 years

(Cl. D34—5)

FIGURE 1 is a front perspective view of a passenger cab for amusement ride showing our new design;

FIGURE 2 is a front elevational view thereof on a reduced scale from that of FIGURE 1;

FIGURE 3 is a rear elevational view thereof on a reduced scale from that of FIGURE 1;

FIGURE 4 is a right side elevational view thereof on a reduced scale from that of FIGURE 1;

FIGURE 5 is a left side elevational view thereof on a reduced scale from that of FIGURE 1; and

FIGURE 6 is a plan view thereof on a reduced scale from that of FIGURE 2.

The dominant feature of our design resides in the portions shown in full lines.

We claim:

The ornamental design for a passenger cab for amusement ride, substantially as shown and described.
